(57) **CLAIM**

The ornamental design for a chair, as shown and described.

DESCRIPTION

FIG. 1 is a right front perspective view of a chair showing the design of the present invention;

FIG. 2 is a front elevation view of a chair showing the design of the present invention;

FIG. 3 is a right side elevation view of a chair showing the design of the present invention;

FIG. 4 is a back elevation view of a chair showing the design of the present invention;

FIG. 5 is a top view of a chair showing the design of the present invention; and,

FIG. 6 is a perspective view of the top portion of the back of a chair showing the design of the present invention.

The broken lines represent environmental elements only and form no part of the claimed design.

1 Claim, 6 Drawing Sheets
